D2-827

AU

EX

D1406

OR

D 022,521

DESIGN.

L. H. WEIL.
CAPE.

No. 22,521.

Patented June 13, 1893.

Witnesses,

Jno. G. Hukel
G. T. Chapman

Inventor,

Leonard H. Weil,
By Joseph Lyons.

Attorneys

UNITED STATES PATENT OFFICE.

LEONARD H. WEIL, OF BALTIMORE, MARYLAND.

DESIGN FOR A CAPE.

SPECIFICATION forming part of Design No. 22,521, dated June 13, 1893.

Application filed April 11, 1893. Serial No. 469,968. Term of patent 3½ years.

To all whom it may concern:

Be it known that I, LEONARD H. WEIL, a citizen of the United States, and a resident of Baltimore, in the State of Maryland, have invented and produced a new and original Design for Capes, of which the following is a specification, reference being had to the accompanying drawing.

The drawing is a perspective view of a fur cape, illustrating my design.

The leading feature of my design consists of a cape as herein shown, the collar of which is represented by a tippet terminating at one end in an imitation of the head of a fur bearing animal, such as a weasel or squirrel, with the fore paws of the animal, one on each side of the head, giving the impression of the animal in repose; while the other end of the tippet is made to resemble the hind feet of the animal and the tail of the same, as shown in the drawing. The body of the cape 1, may be made of any desired material, and is provided with the tippet collar 2. The rear portion 3, of the tippet forms the trimming for one of the front edges of the cape, and the imitation hind paws 4 and tail 5, hang down below the lower edge of the cape, as clearly shown in the drawing. The aesthetic effect produced by this design is that the beholder is persuaded into the belief that a tame weasel or other like animal is seeking refuge with the wearer of the garment.

What I claim is—

The design for a cape, substantially as herein shown and described.

In testimony whereof I have signed my name to this specification in the presence of two subscribing witnesses.

LEONARD H. WEIL.

Witnesses:

THOS. C. BAILEY,
MOSES PIKE.